BILLING MACHINE ALIGNER

Application filed June 17, 1926. Serial No. 116,592.

This invention relates to billing or similar machines, and more particularly in some of its details, it relates to improvements in mechanism for adjusting and aligning the paper record strips used in such machines so as to bring said strips into correct position for the reception of an inscription, and furthermore to tension the strips for a similar purpose.

10 It is a general object of the invention to provide an improved practical mechanism for positioning and aligning one or a plurality of superposed record strips or sheets into correct inscription receiving position on a support 5 or platen, and for relatively aligning the strips where a plurality of superposed strips are employed so as to bring the strips into correct superposed registry.

A further object is to provide in a machine 20 of the class mentioned, an improved manually operable oscillatable strip engaging aligning member, engageable with the strip or strips to positively adjust them into aligned position.

25 Another object is to provide for machines of the class mentioned, an improved aligning mechanism adapted to engage one or a plurality of superposed record strips at parts spaced longitudinally thereof, and to provide an improved operating mechanism to manually move one of the engaging mechanisms longitudinally with reference to the other, so as to positively move the strips into correct position.

35 Still another object is to provide an improved mechanism of the class mentioned which is simple in construction, positive and effective in operation and capable of simple and quick installation on billing or like recording machines of existing construction.

40 Other objects will be in part pointed out in the following detailed description of an illustrative but preferred embodiment of the invention, and will be in part obvious when read in connection therewith.

45 The invention accordingly comprises the features of construction, combinations of elements, and arrangement of parts, which will 50 be exemplified in the construction hereinafter

set forth and the scope of the application of which will be indicated in the claims.

For a more complete disclosure of the nature and objects of the invention, reference is had to the following detailed description, 55 and to the accompanying drawings in which, Figure 1 is a plan view of a billing machine of the flat platen type embodying the invention, parts being broken away or removed to facilitate disclosure;

Fig. 2 is a vertical fragmentary longitudinal section taken substantially upon the line 2—2 of Fig. 1;

Fig. 3 is a detail view of one of the movable or active aligning pins, showing its relation 65 to a strip which is to be aligned;

Fig. 4 is a fragmentary sectional view similar to Fig. 2 but showing the parts in different operative positions; and

Fig. 5 is a fragmentary plan of one of the 70 record strips such as used in the machine.

The improved aligning and tensioning mechanism may be embodied in writing or like machines of different character, but it is particularly adapted for application to billing machines, and may be applied as an attachment to billing machines of existing construction.

Referring to the drawings for a detailed description of the embodiment of the invention there shown, it will be observed that the improved aligning mechanism is applied to a billing machine of the flat platen type over which the writing machine proper travels 80 upon supporting rails in order to effect line 85 spacing.

The supporting frame for the machine may be of any preferred form, the showing of the drawings being somewhat diagrammatic and fragmentary for convenience of illustration. The main supporting framework or base 10 carrying the operative mechanisms of the machine may be supported in any desired manner as by a pedestal or other form of support (not shown). The framework 11 for supporting the track and the record sheets to be written upon may be supported upon the base 10 and includes two parallel longitudinal side rails or bars 12 connected by transverse frame members or cross bars 13. 100

The typewriting machine employed for writing upon the record strips is diagrammatically shown in dot and dash outline at 14 and is mounted upon the longitudinal side rails for movement back and forth thereon over a flat writing platen 15 which supports the record sheets or strips S in flat smooth position for receiving the impact of the type. As will be understood by those familiar with this art, the general arrangement of the record strips and typewriting machine is such as to permit the type to strike upon different parts of the record strips S to impart printed impressions thereto, whereby blank bill forms or like forms upon the strips may be filled in with appropriate data. As it is usually desired to make more than one copy, a plurality of superposed record strips may be employed as shown in the drawings, carbon sheets or similar transverse material being interposed between the adjacent superposed sheets over the platen. If carbon paper is used to transfer the records, the supply thereof may be supported adjacent the platen in any preferred known manner. As many record strips S may be superposed, one on another as desired to provide the required number of copies.

The supply of blank record strips is preferably arranged in the form of a zigzag supply pack or pad S' which may be supported and housed upon or adjacent to the machine in any convenient manner. Each of the record strips may be provided with apertures S² therein which are preferably arranged in two longitudinal series on each strip providing pairs of apertures disposed upon transverse lines of the strips as shown in the drawings. These apertures are utilized for cooperation with strip aligning and tensioning mechanism described below, the pairs of transversely disposed apertures respectively bearing a definite relation to blank forms which may be printed in a longitudinal series upon each of the strips. Also it is desirable that adjacent blank forms on each of the strips be separated by transverse perforated or similarly weakened lines, thus dividing each of the strips into a series of form leaves. These weakened transverse lines aid in severance of the form leaves from the strips after a record has been entered thereon.

In order to retain the record strips in correct position on the platen for reception of an entry or inscription thereon, and to assist in effecting alignment of the strips with reference to each other and to the writing platen, a front strip control device is provided in the vicinity of the platen. This device or strip retaining means may be of different preferred forms than shown being in the form of transverse strip keeper or clamping bar 16 positioned to rest against a cross plate 17 mounted in forwardly inclined position at the front of the machine upon one of the

cross frame members 13. This cross plate is removably clamped in position by means of clamps 18 engaging lugs 19 upon the cross plate and appropriate lugs on the frame of the machine as shown. The cross plate 17 is provided with a pair of upstanding pins or posts 20 preferably flattened or elliptical in cross-section and positioned to enter the apertures formed in the record strips S, and apertures 21 of the clamping bar 16. The major axes of the pins 20 are aligned transversely of the frame and the longitudinally disposed minor axes are considerably shorter than the diameters of the apertures 21, permitting longitudinal adjustment of the cross plate 17 relatively to the clamping bar 16. Also the minor axes of the elliptical pins 20 are considerably shorter than the diameter of the strip apertures so as to permit longitudinal adjustment of the strips when impaled by the aligning pins 20. In the illustrative embodiment disclosed, the pins 20 are rigid and stationary with reference to the cross bar 17 and with reference to the frame of the machine. The clamping bar 16 may serve as a severing edge at the straight forward part thereof for tearing off the form sheets from the supply strips, and the pin supporting cross plate 17 underlying the clamping bar is cut away at its forward edge to provide a recess to facilitate grasping of the forward edges of the strip.

Movement of the strip keeper, or clamping bar 16 to and away from the cross plate 17 to grip and release the underlying record strips may be provided for as shown in the drawings by means of a system of levers controlled by a rod or link 23 connected to a manual operating member, as a pedal 24 pivoted to a supporting standard or column 105 depending from and mounted upon the base plate 10. As shown the clamping bar 16 at its opposite ends is connected to and supported by levers 26 pivoted to the side rails 12 by means of a transverse rod 27 extending through the levers and attached at its opposite ends to the side rails. Each of the levers 26 is furthermore articulated to the adjacent side rail by means of a link 28 loosely pivoted to the lever 26 at 29, and pivoted to the adjacent side rail at 30. The rock arms or levers 26 are biased to hold the clamping bar in gripping position by means of one or a plurality of tensioning springs 31 anchored to the frame and to the lugs 32 depending from the rock arms. A U-shaped operating lever or yoke 33 is pivoted through its opposite legs to the adjacent links 28 by means of a pivotal rod 34, the legs of the yoke extending beyond this pivotal rod 125 to underlie and contact with the rod 27 which thus acts as an abutment or fulcrum for the legs of the U-lever when it is rocked by the pedal to operate the clamping rod. The pedal rod 23 may be connected by means of 130

5 a hook at its upper end to the U-lever 33. By means of this mounting the clamping bar 16 and the operating connections therefor; it will be seen that depression of the pedal will raise the clamping bar to release its grip upon the strips, while the bar is returned to gripping position by operation of the springs 31 when pressure upon the pedal is released.

10 Positioned rearwardly of the platen is another strip engaging mechanism which is active in positioning and aligning the strips. This mechanism includes a rock shaft 35 extending transversely of the frame of the machine and connected to be rotated in strip aligning direction by raising of the pedal. 15 These operating connections include a crank arm 36 secured to the rock shaft 35 and connected by a link or pin coupling member 37 with one arm of a bell-crank lever 38 pivoted to a bracket 39 which may be detachably attached to one of the cross frame members 13. The opposite arm of the bell-crank lever 38 is positioned to lie in a notch or aperture 40 formed in a connecting block or link 41 which is clamped in position upon the bow of the U-shaped lever or yoke 33. The rod or link 37 is preferably connected to the crank 36 by means of a crank pin 42 rotatably mounted in an aperture in the crank and held therein by a cotter pin or similar securing means. The end of the operating link extends slidably through an opening in the head 43 of the crank pin and is secured by lock nuts 44 on the link at one side only of the crank pin head so as to permit the connecting link to slide through the crank pin, thus providing a lost motion connection between the pedal and the rock shaft 35. At its opposite end the operating link 37 is securely connected to a crank pin 45 on the bell-crank lever 38, being similar to crank pin 42 and the link being secured against longitudinal sliding movement through the crank pin by nuts 46 threaded on the link and positioned at both sides of the crank pin.

45 The rock shaft 35 is preferably mounted at its opposite ends in supporting plates or brackets 47 spaced apart so as to lie with their outer faces against the inner faces of the side bars 12. These supporting brackets 50 are arranged to be clamped and supported in position on the machine frame by clamps 48 preferably attached to the brackets and spanning the lower edges of the side rails and secured to said side rails by set screws or 55 similar securing means. Secured also to the supporting brackets 47 and extending transversely of the machine frame are structural tie bars 49 and 50 which may also function as strip guiding and supporting rods, and an additional strip guiding and supporting rod 51 having edge guiding flanges 52 thereon for positioning the strips edgewise as they pass onto the bed of the machine 60 from the supply pad. A unitary guiding

and aligning member is thus provided by the bracket plates 47 and parts supported thereby which may readily be placed upon or removed from the billing machine. It will be seen from the above description that the entire strip aligning and tensioning attachment together with operating connections therefor may readily be applied to billing or like machines of existing construction with a minimum of labor and effort and without alteration or impairment to the machine construction and without interruption to the normal operative functions of the machine.

70 A second strip control device is disposed in rear of the front strip control device, this rear device comprising a pair of rigid strip aligning pins 53 both of similar construction and rigidly mounted upon the rock shaft 35 normally standing in an upright position above the shaft so as to contact with the under surface of the record strips and to enter the aligning apertures therein the pins 53 being thus pivotally, oscillatably shiftable toward and from the front strip control as well as in and out of the path of the strip. Each 80 aligning pin is provided at its outer end with a rigid strip engaging nose or extension 54 of decreased cross-sectional area and flattened in a direction longitudinal of the machine so as to facilitate entry into the strip aligning apertures. The aligning pin extensions are rounded at their rearward or strip engaging sides to form substantially cylindrical surfaces so as to contact with an arc of 85 considerable extent of the strip aligning 90 apertures, providing a large contact surface. A shoulder 55 is formed on the pin at the base of the extension 54 to function as a rest or stop to limit penetration of the pin extension through the apertures of the strips.

95 The rock shaft 35 is preferably biased for rotation to move the aligning pins forwardly in the direction of movement of the record strips, this biasing function being accomplished in the embodiment shown by means of a weight 56 mounted upon an arm attached to the shaft 35 as shown. The aligning pins may thus be yieldingly rocked in one direction, that is forwardly in strip disengaging direction, by this gravity means, 100 while they are rocked in the opposite or strip aligning direction by positive aligning action of the pedal mechanism.

105 The objects and nature of the invention having been set forth and an illustrative embodiment having been disclosed in detail, operation of the invention will now be understood, and for emphasis and clearness may be summarized as follows.

110 The pedal of the machine being depressed to raise the clamping bar 16 and to permit the aligning pins to be rocked forwardly under the influence of the weight 56, the strips may then be threaded over the guide bar 51, over the writing platen, and under the clamp 115

ing bar where the forward aligning apertures of the strips are entered by the stationary aligning pins 20. Pressure upon the pedal is then released when the operating elements are positively returned to normal position under the influence of the spring 31 which is relatively heavy and of sufficient strength to positively force the connected operative elements into final position. During this action, the rock shaft is rocked rearwardly to positively rock the aligning pins in strip aligning direction, causing the ends of the rigid pin projection 54 to wipe or slide over the underface of the record strips as shown in Fig. 3. When the strip aligning apertures are reached, the pin extensions are thus caused to enter the apertures, the rounded or cylindrical rearward sides of the extension then contacting with the rearward sides of the apertures. Continued rearward movement of the aligning pin extensions positively pulls the strips rearwardly to tension them and to bring them into correct position on the writing platen. If the strips chance to be slightly relatively disaligned longitudinally, this action of the aligning pins is effective also to align the strips longitudinally relatively to each other to bring the blank forms thereon into correct superposed registration.

It will be seen that as the operating elements of the mechanism move from the position shown in Fig. 4 to the position of Fig. 2 the bell crank lever 38 will be rocked in a clockwise direction by engagement of the forwardly extending arm thereof with the upper edge of the cam lug 40°. As the movement progresses the said lever arm is withdrawn from the slot 40 and the end thereof comes into contact with the adjacent side or face of the cam lug 40° as shown in Fig. 2. The effect of this action is to positively lock the pin through the rigid operating connections described to engage the adjacent strip aligning apertures S² and thus effect positive alignment of the strips. The pin furthermore is positively locked in final strip aligning position because of the fact that the cam lug 40° contacts with the end of the adjacent bell crank lever arm so as to obstruct the bell crank lever against counterclockwise rocking movement. As mentioned, the spring 31 is a heavy spring and of sufficient strength to move the operating mechanism of the machine to normal position and the paper strips S are ordinarily in practice of insufficient strength to effect forward rocking movement of the aligning pins even when the parts are in intermediate position with the horizontal arm of the bell crank lever projecting into the slot 40. In other words, the walls of the aligning apertures 52 are ordinarily of insufficient strength to pull the aligning pins forwardly against the resistance of the operating spring 31. As above stated the aligning pins are

positively locked in final aligning position and cannot therefore be moved forwardly until the lock is released. The stop lug 57 mounted upon the counter-weight 56 is positioned to contact with the bracket 48 to prevent rearward movement of the aligning pins 54 beyond the final aligning position thereof. Since the counter-weight 56 may be angularly adjusted upon the shaft 35, this lug 57 may therefore be adjusted to different limiting positions.

The aligning pins are in final aligning position when the end of the horizontal arm of the bell crank lever comes into contact with the face of the cam lug 40° and no further movement is imparted to the aligning pins or the operating connections therefor, although the clamping bar 16 and the bracket 41 continue to move with movement of the pedal until the clamping bar is in final clamping position, the end of the bell crank lever arm sliding idly over the face of the cam lug 40°. This provides a convenient arrangement to effect alignment of the strips prior to the clamping thereof by the clamping bar 16, thus permitting the free and unobstructed aligning movement of the strips. During this aligning action of the aligning pins 53, it will be understood that the strips are impaled at forward parts thereof upon the stationary pins 20, but the strip aligning apertures being of greater diameter than the minor axes of the pins 20, relative longitudinal movement of the strips is permitted while at the same time the forward ends of the strips are restrained within certain limits. When the clamping bar is set into clamping position on the strips, the strips are positively held in correct smooth tensioned position over the platen for entry of a record thereupon. It will be understood that the record made upon the top record strip is transferred to the underlying strips by means of transfer sheets interposed between adjacent record sheets in a manner well known in the art; for convenience of illustration, these transfer or carbon sheets are not shown in the drawings.

When an entry has been completed upon the record strips positioned as described above, the pedal is depressed and the operative elements of the machine move from the position shown in Fig. 2 to that shown in Fig. 4, the clamping bar 16 being first released to free the strips and the lug 40° subsequently contacting with the arm of the bell crank lever 38 to slide or project the connecting rod 37 idly through the crank pin head 48 of the crank arm 36. This operation frees the rock shaft and aligning pins 53 to all restraint to forward movement thereof. The pins may actually be moved either by the feeding movement of the strips or by the yielding or impositive action of the weight 56 which tends to rock the pins forwardly to strip disengaging position. Due to this yielding operation

- eration of the aligning pins, tearing or other damage to the strips is avoided, which otherwise might occur if the pins were positively moved forwardly against the forward sides 5 of the strip apertures when the pedal is depressed. The clamping bar being released and the aligning pins freed to forward movement as described, the strips are then pulled forward manually by grasping the forward 10 ends thereof which project into the opening in the forward edge of the cross plate 17, fresh blank forms of the strip being thus brought into position over the writing platen. During this strip advancement, the pins 53 15 are rocked forwardly under the biasing influence of the weight 56, aided also by the strip advancement, whereby they are gradually and smoothly disengaged from the strip apertures, pulling or undue stress upon the 20 walls of the aligning apertures and consequent damage to the strips being thus avoided. The next successive strip aligning apertures being placed over the stationary pins 20, the pressure on the pedal is released and 25 the cycle of operations as above described is repeated. The forwardly fed inscribed ends of the record sheets may then be severed from the strips across the forward edge of the clamping bar 16.
- 30 It will be noticed that the normal position of the strips "S" in their path to the platen is substantially tangential to the arc of the swinging movement of aligning pin 54. This tangential relation enables the aligning pin 35 in its strip aligning movement to slide along the under surface of the record strip, thus to seek strip apertures and enter them when coming into alignment therewith. Continued movement of the pin will effect strip 40 alignment in the manner described. Also, by virtue of this tangential relation, the aligning pin is enabled to be withdrawn from aperture engaging position when moved oppositely to strip aligning direction after being released to free movement in this direction by actuation of the operating mechanism as described.
- 45 Since certain changes may be made in the above construction and different embodiments of the invention could be made without departing from the scope thereof, it is intended that all matter contained in the above description or shown in the accompanying drawings shall be interpreted as 55 illustrative and not in a limiting sense.
- It is also to be understood that the following claims are intended to cover all of the generic and specific features of the invention herein described, and all statements of the scope of the invention which, as a matter of language, might be said to fall therebetween.
- Having described my invention, what I claim as new and desire to secure by Letters Patent, is:
- 60 1. In an apparatus of the character de-
scribed, in combination, a front strip control device, a rear strip control device, said rear device being shiftable toward and from the other, and manually actuatable mechanism operable to impart shift movement to said 65 shiftable device, said shiftable device including a strip aligning pin adapted to engage apertures in the strip and pivotally oscillatable in a path intersecting that of the strip and toward and from said front strip control device, said mechanism including a pin coupling member movable in one direction positively to shift said pin from said front device, and movable relative to said 70 pin in the opposite direction.
2. In an apparatus of the character de-
scribed, in combination, a front strip control device, a rear strip control device, said rear device being shiftable toward and from the other, and manually actuatable mechanism 75 operable to impart shift movement to said shiftable device, said shiftable device including a strip aligning pin adapted to engage apertures in the strip and pivotally oscillatable in a path intersecting that of the strip and toward and from said front strip control device, said mechanism including a pin coupling member movable in one direction positively to shift said pin from said front device, and movable relative to said 80 pin in the opposite direction.
3. In an apparatus of the character de-
scribed, in combination, a front strip control device, a rear strip control device, said rear device being shiftable toward and from the other, and manually actuatable mechanism 85 operable to impart shift movement to said shiftable device, said shiftable device including a strip aligning pin adapted to engage apertures in the strip and pivotally oscillatable in a path intersecting that of the strip and toward and from said front strip control device, said mechanism including a pin coupling member movable in one direction positively to shift said pin from said front device, and movable relative to said 90 pin in the opposite direction, said pin being biased for pivotal shift movement toward said front device and away from the path of the strip.
4. In an apparatus of the character de-
scribed, in combination, a front strip control device, a rear strip control device, said rear device being shiftable toward and from the other, and manually actuatable mechanism 95 operable to impart shift movement to said shiftable device, said shiftable device including a strip aligning pin adapted to engage apertures in the strip and pivotally oscillatable in a path intersecting that of the strip and toward and from said front strip control device, said mechanism including a pin coupling member movable in one direction positively to shift said pin from said front device, and movable relative to said 100 pin in the opposite direction, said pin being biased for pivotal shift movement toward said front device and away from the path of the strip.
5. In an apparatus of the character de-
scribed, in combination, a front strip control device, a rear strip control device, said rear device being shiftable toward and from the other, and manually actuatable mechanism 105 operable to impart shift movement to said shiftable device, said shiftable device including a strip aligning pin adapted to engage apertures in the strip and pivotally oscillatable in a path intersecting that of the strip and toward and from said front strip control device, said mechanism including a pin coupling member movable in one direction positively to shift said pin from said front device, and movable relative to said 110 pin in the opposite direction, said pin having a weight-arm biasing it for pivotal shift movement in an aperture-disengaging direction.
6. In an apparatus of the character de-
scribed, in combination, a front strip control device, a rear strip control device, said rear device being shiftable toward and from the other, and manually actuatable mechanism 115 operable to impart shift movement to said shiftable device, said shiftable device including a strip aligning pin adapted to engage apertures in the strip and pivotally oscillatable in a path intersecting that of the strip and toward and from said front strip control device, said mechanism including a pin coupling member movable in one direction positively to shift said pin from said front device, and movable relative to said 120 pin in the opposite direction, said pin having a weight-arm biasing it for pivotal shift movement in an aperture-disengaging direction.
7. In an apparatus of the character de-
scribed, in combination, a front strip control device, a rear strip control device, said rear device being shiftable toward and from the other, and manually actuatable mechanism 125 operable to impart shift movement to said shiftable device, said shiftable device including a strip aligning pin adapted to engage apertures in the strip and pivotally oscillatable in a path intersecting that of the strip and toward and from said front strip control device, said mechanism including a

- pin coupling member movable in one direction positively to shift said pin from said front device, and movable relative to said pin in the opposite direction, said front strip control device including a fixed aligning pin adapted to engage apertures in the strip, and a strip keeper movable, by operation of said actuating mechanism, into and out of strip control position relative to said fixed pin.
- 10 5. In an apparatus of the character described, in combination, a front strip control device, a rear strip control device, said rear device being shiftable toward and from the other, and manually actuatable mechanism operable to impart shift movement to said shiftable device, said rear device including a strip-aligning pin adapted to engage apertures in the strip and pivotally oscillatable in a path intersecting that of the strip and 20 toward and from said front strip control device, said front strip control device including an aligning pin and a keeper having movement relative to each other to engage and release the strip, said actuating mechanism including devices for imparting shift movement to said rear pin and for effecting said relative movement between said keeper and said front aligning pin, said last mentioned devices including a coupling rod movable in one direction positively to shift said rear pin from said front device, and movable relative to said rear pin in the opposite direction, and means adapted positively to effect movement of said coupling rod in each 35 direction.
6. In an apparatus of the character described, in combination, a front strip control device, a rear strip control device, said rear device being shiftable toward and from the other, and manually actuatable mechanism operable to impart shift movement to said shiftable device, said rear device including a strip-aligning pin adapted to engage apertures in the strip and pivotally oscillatable 40 in a path intersecting that of the strip and toward and from said front strip control device, said front control device including an aligning pin and a keeper having movement relative to each other to engage and release the strip, said actuating mechanism including devices for imparting shift movement to said rear pin and for effecting said relative movement between said keeper and said front aligning pin, said last mentioned 55 devices including a coupling rod movable in one direction positively to shift said rear pin from said front device, and movable relative to said rear pin in the opposite direction, and means adapted positively to effect movement of said coupling rod in each direction, said last mentioned means including a reciprocal cam-lug having a slot, and a bell crank, coupled to said rod, and actuated by said cam-lug.
- 60 65 7. In a strip aligning device for billing

machines or the like, in combination, a platen for supporting one or a plurality of record strips in inscription receiving position, a pair of rigid strip aligning pins positioned at the rear of said platen, mechanism for mounting said aligning pins for rocking movement longitudinally of the strip and in a plane disposed at an angle to the face of said strip, a manual operating mechanism connected to said pin mounting mechanism to positively rock said pins rearwardly into engaging position with apertures in the record strip to effect rearward longitudinal strip aligning movement, and yieldable operating mechanism to yieldingly rock said pins forwardly to disengage the strip.

8. In a strip aligning device for billing machines or the like, in combination, a platen for supporting one or a plurality of record strips in inscription receiving position, a pair of rigid strip aligning pins positioned at the rear of said platen, mechanism for mounting said aligning pins for rocking movement longitudinally of the strip and in a plane disposed at an angle to the face of said strip, a manual operating mechanism connected to said pin mounting mechanism to positively rock said pins rearwardly into engaging position with apertures in the record strip to effect rearward longitudinal strip aligning movement, yieldable operating mechanism to yieldingly rock said pins forwardly to disengage the strip, a strip clamping device positioned forwardly of said aligning pins, and operating connections for said clamping device controlled by said manual operating mechanism so as to set said clamping device subsequently to strip aligning action of said pins while said pins are held in final aligning position by said operating mechanism.

9. In a strip aligning device for billing machines or the like, in combination, a platen for supporting one or a plurality of record strips in inscription receiving position, a pair of rigid strip aligning pins positioned at the rear of said platen, mechanism for mounting said aligning pins for rocking movement longitudinally of the strip and in a plane disposed at an angle to the face of said strip, a manual operating mechanism connected to said pin mounting mechanism to positively rock said pins rearwardly into engaging position with apertures in the record strip to effect rearward longitudinal strip aligning movement, means independent of said manual operating mechanism to rock said pins forwardly to disengage the strip, a pair of strip engaging pins positioned forwardly of said platen for engagement with the apertures in the strip during strip aligning action of said rocking aligning pins, a strip clamping device positioned adjacent said second mentioned strip aligning pins, and operating connections for said clamping device controlled by said manual operating mecha-

- nism so as to set said clamping device subsequently to strip aligning action of said rocking pins.
10. In a strip aligning device, in combination, a rigid carrier and a rigid strip aligning pin rigidly connected thereto and carried thereby and adapted to enter apertures in a strip in effecting strip alignment, means for mounting said carrier for oscillatory movement, actuating means for controlling oscillatory movement of said carrier and operating connections between said carrier and said actuating means to transmit positive movement to said pin in strip aligning direction to effect strip alignment and to positively hold said pin in final strip aligning position, said connections including means to permit free opposite pin movement into strip disengaging position independently of the movement of said actuating means. 20
11. In a strip aligning device for billing machines, in combination, a strip aligning element for engaging in apertures in the strip, manual operating means for positively moving said element in strip aligning direction, a lost motion connection between said operating means and said aligning element permitting movement of the latter in the opposite direction independently of said operating means, and yieldable operating means for yieldingly moving said element in said opposite direction into strip disengaging position. 25
12. In a strip aligning device for billing machines, in combination, a rock shaft having rigidly mounted thereon a rigid aligning pin for entering apertures in the strip, actuating means, positive connections in said actuating means for positively moving said shaft to effect strip aligning movement of said pin, and separate means for moving said shaft in the opposite direction, said connections including a lost motion device to permit pin movement by said separate moving means independently of said actuating means. 35
13. In a strip aligning device for billing machines, in combination, a rock shaft having rigidly mounted thereon a rigid aligning pin for entering apertures in the strip, manual operating means having a lost motion connection with said rock shaft to effect strip aligning movement of said pin, and gravity mechanism for operating said shaft in the opposite direction to move the aligning pin into strip disengaging position. 50
14. In a strip aligning device, in combination, an aligning pin mounted for movement to engage a strip, operating mechanism connected to said pin to move the same to effect strip alignment, means operatively controlled by said operating mechanism to free the pin to independent movement from strip aligning position, and biasing means to move said aligning pin from strip aligning posi- 60
- tion independently of said operating mechanism.
15. In a strip aligning device, in combination, means for restraining a strip against feeding movement, operating mechanism for said strip restraining means, a movable aligning pin mounted for engagement with the strip to effect alignment thereof, operating connections connected to transmit energy from said operating mechanism for moving the pin to effect strip alignment, said operating connections including a part permitting free movement of the pin from strip aligning position independently of operation of said operating mechanism, and biasing means to move said aligning pin oppositely to strip aligning movement thereof from strip aligning position independently of concurrent operation of said operating mechanism. 70
16. In a strip aligning device, in combination, a clamp for restraining a strip against feeding movement, operating mechanism for said clamp, a rigid aligning pin movably mounted for engagement with the strip, operating connections connected to transmit energy from said operating mechanism for positively moving said pin to effect positive alignment of the strip, and an operating connection between said operating mechanism and said operating connections for permitting 80
- clamping movement of said clamp after the aligning pin has reached final aligning movement while continuing to hold said pin in final aligning position. 85
17. In a strip aligning device, in combination, a clamp for restraining a strip against feeding movement, operating mechanism for said clamp, a rigid aligning pin movably mounted for engagement with the strip, operating connections connected to transmit energy from said operating mechanism for positively moving said pin to effect positive alignment of the strip, and a controlling connection between said operating mechanism and said operating connections for permitting 90
- clamping movement of said clamp after the aligning pin has reached final aligning movement while continuing to hold said pin in final aligning position. 95
18. In a strip aligning device, in combination, a clamp for restraining a strip against feeding movement, operating mechanism for said clamp, a rigid aligning pin movably mounted for engagement with the strip, operating connections connected to transmit energy from said operating mechanism for positively moving said pin to effect positive alignment of the strip, a controlling connection between said operating mechanism and said operating connections for permitting clamping movement of said clamp after the aligning 100
- pin has reached final aligning movement while continuing to hold said pin in final aligning position, said pin operating connections including means to free said pin 105
- to independent movement from final aligning position when said operating mechanism is operated to release said clamp. 110
19. In a strip aligning device, in combination, a clamp for restraining a strip against feeding movement, operating mechanism for said clamp, a rigid aligning pin movably mounted for engagement with the strip, operating connections connected to transmit energy from said operating mechanism for positively moving said pin to effect positive alignment of the strip, a controlling connection between said operating mechanism and said operating connections for permitting clamping movement of said clamp after the aligning 115
- pin has reached final aligning movement while continuing to hold said pin in final aligning position, said pin operating connections including means to free said pin 120
- to independent movement from final aligning position when said operating mechanism is operated to release said clamp. 125
20. In a strip aligning device, in combination, a clamp for restraining a strip against feeding movement, operating mechanism for said clamp, a rigid aligning pin movably mounted for engagement with the strip, operating connections connected to transmit energy from said operating mechanism for positively moving said pin to effect positive alignment of the strip, a controlling connection between said operating mechanism and said operating connections for permitting clamping movement of said clamp after the aligning 130

pin has reached final aligning movement while continuing to hold said pin in final aligning position, and separate means for biasing the aligning pin for movement oppositely to strip aligning movement thereof from final aligning position.

19. In a strip aligning device, in combination, a clamp for restraining a strip against feeding movement, operating mechanism for said clamp, a rigid aligning pin movably mounted for engagement with the strip, operating connections to said operating mechanism for positively moving said pin to effect positive alignment of the strip, a controlling connection between said operating mechanism and said operating connections for permitting clamping movement of said clamp after the aligning pin has reached final aligning movement while continuing to hold said pin in final aligning position, said pin operating connections including means to free said pin to independent movement from final aligning position when said operating mechanism is operated to release said clamp, and separate means for biasing the aligning pin for movement oppositely to strip aligning movement thereof from final aligning position when free to independent movement.

20. In a strip aligning device, in combination, an aligning pin mounted for movement to enter an aligning aperture in a strip, means to operate said pin to exert an aligning influence on the strip oppositely to the direction of strip advancement, and means effective when the pin is in engagement with an aligning aperture for rendering said pin incapable of exerting restraint on the strip oppositely to direction of travel thereof.

21. In a strip aligning device, in combination, a rockable member, a rigid aligning pin mounted adjacent said rockable member and operatively connected thereto for movement thereby, and operating mechanism for said rockable member to rock the pin in one direction and including a lost motion connection so as to be incapable of moving the rockable member in the opposite direction.

22. In a strip aligning device, in combination, an aligning pin movably mounted for engagement with a strip, operating mechanism connected to said aligning pin to move the same to effect strip alignment and a rigid locking mechanism for locking said aligning pin in final strip aligning position.

23. In a strip aligning device, in combination, an aligning pin movably mounted for engagement with a strip, operating mechanism connected to said aligning pin to move the same to effect strip alignment, locking mechanism for locking said aligning pin in final strip aligning position, and means controlled by said operating mechanism for setting said locking mechanism when said pin reaches said final aligning position.

24. In a strip aligning device, in combina-

tion, an aligning pin movably mounted for engagement with a strip, operating mechanism connected to said aligning pin for moving the same to effect strip alignment, said operating mechanism including a reciprocal cam lug and a lever having a lost motion operative connection with said cam lug.

25. In a strip aligning device, in combination, an aligning pin movably mounted for engagement with a strip, operating mechanism connected to said aligning pin for moving the same to effect strip alignment, said operating mechanism including a lever and connections for positively moving said lever in opposite directions, said connections including a reciprocal cam lug slidably contacting with said lever so as to block movement of the latter in one direction.

26. In a strip adjusting device for machines of the class mentioned, in combination, an adjusting pin mounted for movement to engage a strip, operating mechanism connected to said pin to move it to effect strip adjustment and means operatively controlled by said operating mechanism to release the pin to free movement independently of the operating mechanism reversely of strip aligning movement from strip aligning position.

27. In a strip adjusting device for machines of the character described, in combination, a strip adjusting pin, mounting means for supporting and positioning said pin for oscillation in tangential relation to the path of the strip so as to move said pin into strip adjusting position and to adjust the strip, operating means controlling movement of said pin to engage and adjust the strip and means controlled by said operating means to release said pin to movement independently of the operating means reversely to its strip aligning movement.

28. In a strip adjusting device for machines of the character described, in combination, a platen for supporting one or a plurality of apertured record strips in inscription receiving position, a strip holding device positioned relatively forward of said platen, a strip controlling device positioned relatively rearwardly of said platen and including a swingable carrier on which a rigid aligning pin is rigidly mounted for unitary movement therewith in forward and reverse directions, said pin and the record strip being positioned in tangential relation with each other whereby said swinging movement of said carrier away from said strip holding device moves the aligning pin into engagement with a strip aperture and effects strip alignment and a unitary operating means for controlling said holding action of said holding device and for controlling the strip adjusting movement of said swingable carrier.

29. In a mechanism of the character described, a table to support a plurality of superimposed apertured webs, a device pivot-

ally mounted at one end of said table for movement about an axis substantially parallel with said table and adapted to extend through the apertures in said webs and to adjust said webs with relation to each other, and a device for imparting pivotal movement to said adjusting device and for holding the adjusted webs against movement.

6 In testimony whereof I affix my signature.
10 LOUIS FRED HAGEMANN.
